FIRE BASKET.

No. 18,367.

Patented June 5, 1888.

UNITED STATES PATENT OFFICE.

LAZARD KAHN AND RUDOLPH THIEM, OF HAMILTON, OHIO, ASSIGNEES TO
F. & L. KAHN & BROTHERS, OF SAME PLACE.

DESIGN FOR A FIRE-BASKET.

SPECIFICATION forming part of Design No. 18,367, dated June 5, 1888.

Application filed March 22, 1888. Serial No. 268,181. Term of patent 7 years.

To all whom it may concern:

Be it known that we, LAZARD KAHN, a citizen of the United States, and RUDOLPH THIEM, a subject of the Emperor of Germany, residing 5 in Hamilton, Butler county, Ohio, have invented certain new and original Designs for Fire-Baskets, of which the following is a specification, reference being had to the accompanying photograph, forming a part thereof.

10 The photograph represents the fire-basket in perspective. The fire-basket is intended to hold the fire in a fire-place or open-front stove.

15 The leading features by which our design is characterized are as follows: The basket proper, A, is substantially rectangular in plan, but shorter at its rear, and has downwardly and inwardly curving front bars, and the top rim, D, at the ends and front, is upon one level. When viewed in perspective from above, the 20 elements mentioned all appear to tend rearwardly. The back piece, B, projects above the general rim of the basket in the form of a semicircular panel, C, embellished by a scene in relief of artificers working in metal. The 25 base G of this panel projects below the general level of the basket-rim. The rim-piece D surmounts the rim of the basket and projects outside the same, and has a convex upper surface embellished by transverse bead- 30 ings. Snail-shaped cones E project upwardly at intervals from the rim-piece. The front legs, F, represent lions' heads, with greaves below, down out of which project lion-shins

terminating in feet. The rear legs, J, curve outwardly sidewise at top and bottom, and 35 their front faces are embellished in imitation of the side of a lion's shin and foot.

We claim—

A design for a fire-basket, characterized by a grate-formed basket, A, substantially rectangular in form, but shorter at its rear, and having downwardly and inwardly curving front bars and a rim upon the same level at the front and ends; by a back piece, B, in the form of a semicircular panel projecting above 40 the general rim of the basket; by the embellishment C upon such panel representing a scene in relief of artificers working in metal; by a back piece, B, projecting above the general rim of the basket and having its base 45 G projecting below the said rim; by a rim-piece, D, having a convex upper surface embellished by transverse beadings; by snail-shaped cones E, projecting upwardly at intervals from the rim; by front legs, F, representing lion-heads, with greaves below, down out of which project lion-shins terminating in feet; and by rear legs, J, curving outwardly sidewise 50 at top and bottom, with their front faces embellished in imitation of the sides of lions' shins 55 and feet, as shown.

LAZARD KAHN.
RUDOLPH THIEM.
